UNITED STATES PATENT OFFICE.

RICHARD J. WILLIAMS, OF SAN FRANCISCO, CALIFORNIA, ASSIGNEE OF ONE-HALF TO
PETER GRASSI, OF SAN FRANCISCO, CALIFORNIA.

SASH-BALANCE.

1,350,584.

Specification of Letters Patent. Patented Aug. 24, 1920.

Application filed April 1, 1919. Serial No. 286,634.

To all whom it may concern:

Be it known that I, RICHARD J. WILLIAMS, a citizen of the United States, residing at the city and county of San Francisco and 5 State of California, have invented new and useful Improvements in Sash-Balances, of which the following is a specification.

This invention relates to a window construction and particularly pertains to a sash 10 balance.

It is the principal object of this invention to provide a sash weight which may be made of dimensions larger than the opening into the sash pocket of the window frame and 15 will be so designed as to readily pass through these openings without inconvenience.

Another object of this invention is to provide a sash weight, preferably made of 20 plastic material, which, while simple in construction, will at the same time be quite strong and not liable to break loose from its suspension means.

The invention is illustrated by way of 25 example in the accompanying drawings, in which—

Figure 1 is a fragmentary view of a window frame, showing the complementary vertically slidable sash thereof and one of the 30 sash balances therefor.

Fig. 2 is a view in vertical section, illustrating the preferred form of the sash weight, showing the manner in which a cord pulley is detachably secured therein.

Fig. 3 is a view in side elevation, illustrating a modified form of the sash weight.

Fig. 4 is a view in horizontal section, as seen on the line 4—4 of Fig. 1, showing the sectional formation of the sash weight and 40 the manner in which it is inserted into the weight pocket.

Referring to the drawings, 10 indicates a window frame adapted to inclose a lower sash 11 and an upper sash 12. These sashes 45 are vertically slidable and are secured at their opposite sides to sash cords 13. As indicated in dotted lines of Fig. 1, one cord is used at each side of the window frame and its opposite ends are attached to the sashes 50 11 and 12 at the points 14 and 15, respectively. The main portion of the cord 13 passes over a pair of pulleys 16 which are freely mounted upon a common axle 17. The sash cord is thus looped and hangs 55 down within a weight well 18 where it

passes around a pulley 19. As shown in Fig. 2, the pulley 19 is provided to be detachably secured to a pin 20. This pulley is constructed with a hook-member 21 secured to the axle 22 of the pulley and co-operating with a guard plate 23 upon the opposite end of the axle to provide an opening into which the pin 22 may be positioned and from which it is not liable to be accidentally displaced.

The pin 20 is embedded within a concrete sash weight 24 and preferably extends across a pulley pocket 25, represented by a depression in the upper end of the weight. Due to the arrangement of this pocket, the 70 sash cord 13 will remain in proper position upon the pulley groove and will be held without other guide members. The sash weight 24, as formed of concrete, is suitably reinforced by a sheet of reticulated 75 material 26. This material extends downwardly within the body of the weight and is suitably secured to the upper ends of the pin 20.

It is common in window construction 80 to provide the well 18 with a weight opening 27 through which the ordinary cast-iron weights are passed. Due to the fact that in the present instance a weight of substantially twice the sectional area of cast-iron 85 weights is used to counter-balance both window sashes, it is necessary to enlarge the passageway 27 or to alter the form of the weight.

One object of the present invention is to 90 provide a weight of large bulk which may be conveniently passed through the opening 27, as shown in Fig. 4. This is done by making the weight of crescent-shape when considered in transverse section and thereby causing it to be readily inserted and turned through the opening 27, from the dotted line position shown in Fig. 4, to assume the operative position indicated by the solid lines in the same figure.

Reference being had to Fig. 3, it will be seen that the reinforcing member 26 is eliminated and a suitable wire reinforcement 28 provided. This wire is looped at its upper end and is adapted to receive the hook 21 of 105 the pulley 19. In the present case a guard member 29 extends around the pulley and prevents the cord from moving therefrom.

In operation of the present invention, the window sashes are fitted with cords 13 and 110

thereafter the sash weights are inserted through the openings 27, as indicated in Fig. 4. After this has been done, the pins of the weights are engaged by the hooks 21 of the pulleys 19 and at this time the sash cords 13 may be positioned around the pulleys 19. It, of course, may be found desirable to place this cord in position before its ends are attached to the windows.

10 In operation, the elevation of the lower sash or the lowering of the upper sash will be counter-balanced by the movement of the sash weights and when the form of weights shown in Fig. 2, is used, the pulley 19 will be held within the depression of the weight in a manner to prevent accidental removal of the cord 13.

15 It will thus be seen that the structure here disclosed, while decidedly simple, eliminates a number of parts commonly used in window construction and at the same time provides a simple counter-balance for both 20 slidable sashes of the window and also provides an inexpensive and desirable window- 25 weight.

20 While I have shown the preferred form of my invention, it will be understood that various changes in the combination, construction and arrangement of parts may be 30 made by those skilled in the art, without departing from the spirit of the invention as claimed.

Having thus described my invention, what I claim and desire to secure by Letters Patent is—

35 1. A window frame having a vertical weight channel at the side and a removal opening at one side, a weight having transverse dimensions to substantially fill the channel, said weight being crescent shaped 40 in transverse section, with the greatest thickness less than the width of the removal opening of the casing, said weight being turnable with its concavity about the inner edge of the opening to remove it. 45

2. A sash weight adapted to be moved in a guiding wall or channel and having a transverse width approximately equal to the channel width, one wall being formed with a vertical removal opening, the vertical 50 faces of the weight being concavo-convex, and the radial thickness being less than the vertical removal opening of the channel, said weight being turnable with its concavity in contact with the removal opening 55 when passing through it.

In testimony whereof I have hereunto set my hand in the presence of two subscribing witnesses.

RICHARD J. WILLIAMS.
